HERMAN WIRZ, JR., OF LOS ANGELES, CALIFORNIA, ASSIGNOR OF FORTY-NINE ONE-HUNDREDTHS TO CHARLES F. HLAVATY, OF LOS ANGELES, CALIFORNIA

AUTOMATIC SEWER FLUSHER

Application filed December 21, 1931. Serial No. 582,272.

This invention relates to improvements in sewer flushers.

The general object of the invention is to provide an improved automatic device for flushing main sewers with fresh water.

Another object of the invention is to provide an automatic sewer flusher including a water reservoir from which the water is siphoned when the water in the reservoir reaches a predetermined level.

Other objects and advantages of this invention will be apparent from the following description, taken in connection with the accompanying drawing wherein:

Fig. 1 is a vertical section through my improved sewer flusher.

Fig. 2 is a section taken on line 2-2 of Fig. 1.

Fig. 3 is a section taken on line 3-3 of Fig. 1.

Fig. 4 is an enlarged sectional detail, and

Fig. 5 is an enlarged sectional detail of the metering device.

Referring to the drawing by reference characters I have shown a water reservoir tank including the features of my invention generally at 10.

As shown the reservoir 10 is of the type now usually used for the purpose of flushing sewers and I have shown my invention as adapted to be installed in this type of reservoir. The reservoir 10 includes a main portion 12 having a centrally located reduced well 13 therein. To adapt this type of reservoir for my invention a portion of the well 13 is deepened to form a well 14 and a partition wall 15 is provided which terminates below the top of the reservoir and divides the reservoir in two sections 16 and 17. A pipe 18 which communicates with the sewer opens into the well 14.

In the reservoir 12 I provide a siphon device which is indicated generally at 20 and includes a yoke portion 21, a connecting portion 22 and a goose neck portion 23. The yoke portion 21 includes two legs 24 and 25 positioned one on each side of the wall 15 and which communicate with each other by a portion 26 which has a common outlet 26a (see Fig. 4) opening through the top thereof.

The intercommunicating portion 26 is provided with a small vent aperture 26' in the lower wall thereof. The lower ends of the legs 24 and 25 extend downwardly to a point spaced a slight distance above the bottom of the reservoir portion 12. The connecting portion 22 communicates with the yoke outlet 26 and curves as at 27 to one side of the wall 15 into the reservoir portion 17 where it includes a downwardly extending leg 28 which communicates with the inlet 29 of the goose neck portion 23.

The goose neck portion 23 of the siphon includes a downwardly extending portion 30 which extends downward to adjacent the bottom of the well 14 where it rounds into an upwardly extending portion 31 which includes an angular outlet portion 32 which communicates with the pipe 18 to the sewer. On the angular outlet portion 32 of the goose neck I provide a reduced inlet portion 33 having a pipe 34 communicating therewith which extends upwardly to a point above the maximum water level in the reservoir. The pipe 34 serves as an overflow pipe to prevent an excessive amount of water from accumulating in the reservoir should the device become inoperative and also as a vent to allow escape of any sewer gases which back up through the pipe 18.

For filling the reservoir I provide a pipe 35 which extends from a suitable source of water supply (not shown). The pipe 35 extends downwardly to adjacent the wall 15 where it includes a branch portion 36 which extends into the portion 16 of the reservoir and a branch portion 37 which extends into the portion 17 of the reservoir. The branch 36 is provided with an outlet valve 38 which is actuated by a float 39 and the branch 37 is provided with an outlet valve 40 which is actuated by a float 41. The valves 38 and 40 may be any type of float actuated valve desired. The valve 38 is arranged so that when the float 39 moves downwardly a predetermined distance it will open to discharge water therefrom while the valve 40 is arranged so that when the float 41 rises it will open to discharge water therefrom.

The flow of water through the pipe 35 to 100

the valves 38 and 40 may be controlled by a shut-off valve 42.

Adjacent the top of the wall 15 I provide a metering device indicated generally at 45. As shown this device includes a metal plate 46 which is preferably copper, embedded in the wall, and includes a lower aperture 47 and an upper aperture 48. Secured to the plate 46 and extending downwardly at an angle towards the reservoir portion 17 I provide a trough 49. For protecting the metering device 45 from refuse or other foreign matter I preferably provide screen members as indicated at 50.

15 In operation the valve 42 is opened to allow water to flow to the valves 38 and 40. When the valve 42 is opened water will flow to the valve 38 and discharge therefrom into the reservoir portion 16 as the float 39 is in a lowered position and the valve 38 is open. The water flows from the valve 38 into the reservoir section 16 and rises therein until it reaches the metering device 45 whereupon as the water continues to rise it flows through 20 the metering aperture 47 and discharges into the reservoir section 16. As the water rises in the reservoir section 17 and the lower end of the yoke leg 25 becomes submerged the air trapped in the legs 24 and 25 escapes through 25 the vent aperture 26' of the yoke. When the water rises in the reservoir to a point adjacent the top of the wall 15 it raises the float 41 which in turn opens the valve 40 whereupon the valve 40 discharges water into the reservoir section 17.

25 The water continues to flow from the reservoir section 16 through the metering device 45 into the reservoir section 17 until the water levels in both the reservoir sections 16 and 17 are the same. Whereupon the water level in both sections continues to rise and rises above the top of the wall 15 and to a point above the outlet 26a as indicated at A in Fig. 2. As the water rises above the outlet 26a it flows through the connecting portion 22 of the siphon into the goose neck portion 23 and thence into the pipe 18 from which it is discharged into the sewer.

30 As the water thus flows through the goose neck into the pipe 18 it creates a suction which produces a siphon action in the legs 24 and 25 thereby causing the water in both reservoir sections 16 and 17 to be drawn therefrom until the water level in the sections fall below the lower ends of the legs 24 and 25 whereupon the siphon action will cease. As the water in the reservoir sections 16 and 17 falls below a predetermined point the valve 40 will close and the valve 38 will open whereupon water will again be discharged into the reservoir section 16 to again start duplication of the previously described actuation of the device.

35 During the siphon action the small vent 26' will not break the suction due to the large

volume of water passing through the yoke. By varying the size of the apertures 47 and 48 in the metering device, the time required to fill the reservoir section 17 may be varied.

Normally the water flows from the reservoir section 16 through the lower metering aperture 47 into the section 17 but if the aperture 47 should become clogged the water will rise in the section 16 until it reaches the level of the upper aperture 48 and will then flow through the aperture 48 into the reservoir section 17.

40 The reservoir is divided into two portions to enable the metering to be accomplished by the device 45 instead of by float valves 38 and 40. In operation the reservoir portion 16 is rapidly filled by the valve 38 until the level of the water in the reservoir 16 reaches the device 45. The float 39 is set to cause water to flow from the valve 38 only when the water level permits a slight discharge through the device 45. This fills the reservoir 17 very slowly, requiring about 45 twenty-four hours for the operation.

45 When the water in the reservoir 17 reaches the float 41 the valve 40 is opened whereupon the water level rapidly rises to the position shown at A (Fig. 2). When the water has reached this level A the air entrapped in the space 26a and the pipe 30 has a pressure sufficient to bubble through the water in the trap 31. As the air surges through the trap 31 the siphonizing action is started and the water discharges at the full capacity of the siphon.

50 From the foregoing description it will be apparent that I have provided a novel sewer flushing device which is simple in construction and efficient in use.

Having thus described my invention, what I claim is:

55 1. In a sewer flushing device, a reservoir comprising two parts, one of said parts being deeper than the other a conduit leading from said deeper part, a siphon device including a pair of communicating spaced legs positioned with one of said legs communicating with one of said reservoir parts and the other leg with the other of said parts, said device having an outlet, a hollow member connected to said outlet, said hollow member extending down into said deeper part below the said conduit and communicating with said conduit.

60 2. In a sewer flushing device, a reservoir comprising two parts, a conduit leading from one of said parts, a siphon device comprising a pair of communicating spaced hollow legs positioned with one of said legs communicating with one of said reservoir parts and the other leg with the other of said parts, said device having an outlet, a hollow member connected to said outlet, said hollow member extending down into said reservoir and communicating with said conduit.

3. In a sewer flushing device, a reservoir comprising two parts, one of said parts being deeper than the other, a conduit leading from said deeper part, a siphon device, said siphon device including an inverted U-shaped portion comprising a pair of communicating legs positioned with one of the legs communicating with one of said reservoir parts and the other leg with the other of said parts, said U-shaped portion having an outlet, a hollow member connected to said outlet, said hollow member extending down into said deeper part below the said conduit and being bent back upon itself and extending upward and communicating with said conduit. 75
4. In a sewer flushing device, a reservoir, a partition extending across said reservoir and dividing said reservoir into two parts, one of said parts being deeper than the other, a conduit leading from said deeper part, a siphon device, said siphon device including an inverted U-shaped portion comprising a pair of communicating spaced hollow upright legs positioned with one of said legs communicating with one of said reservoir parts and the other leg with the other of said parts, said U-shaped portion having a lateral outlet at the highest point thereof, a hollow member connected to said lateral outlet, said hollow member extending down into said deeper part below the said conduit and being bent back upon itself and extending upward and communicating with said conduit. 80
5. In a sewer flushing device, a reservoir comprising two parts, one of said parts being deeper than the other, a conduit leading from said deeper part, a siphon device including a pair of communicating spaced legs positioned with one of said legs communicating with one of said reservoir parts and the other leg with the other of said parts, said device having an outlet, a hollow member connected to said outlet, said hollow member extending down into said deeper part below the said conduit and communicating with said conduit, means to convey water to each of said reservoir parts, means to control the flow of water into each of said reservoir parts, means whereby when the water level in the shallow reservoir part reaches a predetermined low level water will be admitted to said shallow part and when it reaches a predetermined high level the water will be shut off, and means whereby when the water in said deeper reservoir part rises to a predetermined level water will be admitted to said deeper part and when the water falls below a predetermined level the water will be shut off. 100
6. In a sewer flushing device, a reservoir comprising two parts, one of said parts being deeper than the other, a conduit leading from said deeper part, a siphon device, said siphon device including an inverted U-shaped portion comprising a pair of communicating legs positioned with one of said legs communicating with one of said reservoir parts and the other leg with the other of said parts, said U-shaped portion having an outlet, a hollow member connected to said outlet, said hollow member extending down into said deeper part below the said conduit and being bent back upon itself and extending upward and communicating with said conduit, means to convey water to each of said reservoir parts, means to control the flow of water into each of said reservoir parts, means whereby when the water level in the reservoir part not including said well reaches a predetermined low level water will be admitted to said last part and when it reaches a predetermined high level the water will be shut off, and means whereby when the water in said reservoir part including said well rises to a predetermined level water will be admitted to said last part and when the water falls below a predetermined level the water will be shut off. 115
